[57] ABSTRACT

First and second output voltages are generated respectively in accordance with the logarithm of the intensity of light and as a function of a manually set exposure condition. A control signal to initiate shutter closing is generated when a signal which changes in proportion to the logarithm of an elapsed time period initiated by shutter release operation plus the second output voltage is substantially equal to the first output voltage. The control device includes a circuit for comparing the voltages. The device may be modified to generate a third output voltage which changes in response to the change of the signal and then comparing the first output voltage with the second plus the third output voltage.

**EXPOSURE TIME CONTROL DEVICE FOR A
THROUGH THE LENS TYPE SINGLE REFLEX
CAMERA**

Matter enclosed in heavy brackets **[ ]** appears in the original patent but forms no part of this reissue specification; matter printed in italics indicates the additions made by reissue.

BACKGROUND OF THE INVENTION

The present invention relates to an exposure time control device **[in]** for a "through the lens" type single reflex camera. In a single reflex camera it is impossible to **[ ]** do photometry while in **[ ]** take a photometric measurement during an exposure, so that the photometric value prior to exposure is **[ ] memorized** stored by a **[ ] memory condenser** capacitor so as to control the exposure **[ ] through said memory** by the stored voltage. However, in order to **[ ] memorize** store a wide range of **[ ] the** object brightness **[ ]** in the memory condenser **[ ]** a means has been adopted for giving a logarithmic compression to the illuminance on the light receiving surface of a photoconductive element and **[ ] memorizing the** storing a voltage **[ ] given said** representing that logarithmic compression in the **[ ] memory condenser** storage capacitor.

And, up to the present time, when the exposure is controlled **[ ] through said memory voltage** the **[ ] memory** stored voltage **[ ] given said logarithmic compression** is given **[ ] the** an inverse-logarithmic conversion by a **[ ] logarithm elongation** conversion element and the exposure control circuit is operated by the output thereof.

However, in the case **[ ] of that** where the inverse-logarithmic conversion is **[ ] given by the logarithm elongation element** provided the voltage variation quantity given the logarithmic compression **[ ] for giving** representing 1 EV of variation relative to the exposure value **[ ] through the output elongated** is restricted by the characteristic of **[ ] said logarithm elongation** the conversion element **[ ]**, and as the result **[ ]**. Thus, the voltage variation **[ ] quantity** per 1 EV **[ ] in progress** of the logarithmic compression is very small, therefore, errors are **[ ] easy to intervene** generated, resulting in **[ ] dropping remarkably** a degradation of the precision in **[ ] progress of the logarithm elongation** the conversion process.

OBJECTS OF THE INVENTION

One object of the present invention is to provide an *improved* exposure time control device in a "through the lens" type single reflex camera, which **[ ]** is removed from **[ ]** overcomes the prior drawbacks mentioned above and controls the exposure time without **[ ] giving** the necessity of the inverse-logarithmic conversion. **[ ] to the memory voltage given the logarithmic compression**.

Another object of the present invention is to provide an exposure time control device in a "through the lens" type single reflex camera, which is able to set up optionally the voltage variation quantity per 1 EV in the logarithmic compression process.

FEATURES OF THE INVENTION: **[ ] SUMMARY
OF THE INVENTION**

5 **[ ]** Further another object **[ ]** One feature of the present invention is to provide an exposure time control device in a "through the lens" type single reflex camera, which is so formed that the **[ ] memory** stored voltage **[ ] given said logarithmic compression** is compared with the output voltage of the reference time integrating circuit, which output voltage increases in proportion to the logarithmic value **[ ] of the time** from the exposure starting time by means of a comparison circuit, and when **[ ] said** both voltage coincide with each other the exposure is **[ ] ended and controlled** terminated.

Still **[ ]** further **[ ]** another **[ ] object** feature of the present invention is to provide an exposure time control device in a "through the lens" type single reflex camera, which is so formed that **[ ] as a comparison circuit** a differential amplifier circuit is **[ ] put to use** used as a comparison circuit, and **[ ] to the emitter and collector circuits of a transistor having the **[ ] memory** stored voltage of the **[ ] memory condenser** storage capacitor as one input of **[ ] said** the differential amplifier circuit and the fixed base electric potential as the other input **[ ]**, condensers are respectively connected, and the **[ ]**. The charging voltage of the **[ ] condenser** capacitor in **[ ] said** the collector circuit is impressed on the differential amplifier and when both input voltages become equal the output of **[ ] said** the differential amplifier circuit operates the switching circuit for the exposure control circuit.**

Still **[ ]** further **[ ]** another **[ ] object** feature of the present invention is to provide an exposure time control device in a "through the lens" type single reflex camera, which controls the exposure corresponding to photographic conditions by connecting a bias resistance for film sensitivity **[ ] change** and stop value changes to an input **[ ]** condenser impressed in **[ ]** capacitor of the differential amplifier circuit.

Still **[ ]** further **[ ]** yet another **[ ] object** feature of the present invention is to provide an exposure time control device in a "through the lens" type single reflex camera, which compensates for the fluctuation of **[ ]** an **[ ]** electric power source voltage.

SUMMARY OF THE INVENTION: **[ ]**

In order to attain the above-mentioned objects and features, the *apparatus* of the present invention **[ ]** relates to an exposure time control device in a "through the lens" type single reflex camera, which **[ ]** is so constructed that there are provided a **[ ] memory condenser** storage capacitor for **[ ] memorizing** storing the output voltage of a photometric circuit for detecting the voltage proportional to the logarithmic value of the illuminance on the light receiving surface of a photoconductive element prior to exposure **[ ]**, and a **[ ]**. A reference time integrating circuit **[ ] which** is included having an output voltage which increases in proportion to the logarithmic value **[ ] of the time** from the exposure starting time, and to one **[ ] side** input of a comparison circuit the **[ ] memory** stored voltage **[ ] of said memory condenser** is **[ ] input** connected and to the other **[ ] side** input of **[ ] said** the **[ ] comparative** comparison circuit the output voltage of **[ ] said** the reference time integrating circuit is **[ ] input, and said both** connected. Both voltages are compared to each other by **[ ] said** the comparison circuit and when they

coincide with each other the output of [said] the comparison circuit operates an exposure time control circuit [; wherein since] . Since the comparison circuit compares the voltage proportional to the logarithmic value of the illuminance on the light receiving surface of the photoconductive element directly with the voltage proportional to the logarithmic value of the exposure time the device has no need [of] for a means for converting the [memory] stored voltage of the [memory condenser to] storage capacitor by the inverse logarithm technique.

BRIEF DESCRIPTION OF THE DRAWINGS

FIG. 1 is a block diagram of the circuit showing the fundamental formation of the present invention.

FIG. 2 is the exposure time control circuit diagram in the exposure time control device in a "through the lens" type single reflex camera in accordance with the present invention.

FIG. 3 is an enlarged circuit diagram of the essential portion of [said] the circuit of FIG. 2.

FIG. 4 is a diagram showing the relation between the logarithmic value of the time and the charging voltage after the fixed base voltage constituting the reference time integrating circuit [in accordance with the present invention] is impressed and the trigger switch for the condenser inserted in the collector circuit of the transistor is closed.

FIG. 5 is a circuit diagram of the composite photoconductive element showing an example of the light receiving element in the present invention.

FIG. 6 is a diagram showing the relation between the illuminances on the light receiving portion of [said] the composite photoconductive element and on the light receiving face of the fixed resistance, and the respective [resistance value] resistances thereof.

FIG. 7 is a partial view of the photometric circuit in which the composite photoconductive element shown in FIG. 5 is connected in series to the fixed resistance.

FIG. 8 is a diagram showing the relation between the electric potential at the connection point in the circuit shown in FIG. 7 and the light receiving illuminance.

FIG. 9 is a perspective view showing the essential portion of an embodiment of the exposure time control device in accordance with the present invention.

FIG. 10 shows a circuit diagram making use of two composite photoconductive elements in the light receiving portion of another embodiment in accordance with the present invention.

DESCRIPTION OF THE PREFERRED EMBODIMENT

FIG. 1 shows the principle of the present invention, wherein the information [of] representing the the brightness of an object coming into photoreceiving portion (i) is [compressed by logarithmic] logarithmically compressed by circuit (ii) and then comes into memory circuit (iii). Just prior to exposure, photoreceiving portion (i) is disconnected from memory circuit (iii) and the information [of] representing the brightness of the object just prior to photographing is [memorized] stored by memory circuit (iii) [, however, it] . However, the logarithmically compressed value is [memorized by receiving the logarithmic compression] stored so that it is possible to [be memorized in good precision to] store the object brightness covering a wide range [coming up to scores of thou-

sands times] of a few orders of magnitude between the highest and the lowest value with good precision.

The information [memorized] stored by memory circuit (iii) [comes into] is provided to comparison circuit (iv).

The information in film sensitivity and stop adjusting circuit (v) comes into operation circuit (vii) together with the information in reference time integrating circuit (vi) which output is in proportion to the logarithmic value [of] from the time [from] of the start of exposure [starting, to be operated therein, and the] . The information in operation circuit (vii) [comes into] is also provided to comparison circuit [vi] (iv) to be compared with the information in the memory circuit (iii), and when the information [in] from operation circuit (vii) becomes equal to the information [in] from memory circuit (iii) [the] a relay [for] in exposure time control circuit (viii) is reversed and the exposure time is controlled.

20 The information of the object brightness in logarithmic compressed circuit (ii) and the information in film sensitivity and stop adjusting circuit (v) [come] are also [into] provided to meter circuit (ix) to indicate the shutter speed.

25 FIG. 2 shows the exposure time control circuit of an embodiment in accordance with the present invention.

Photoconductive element R_0 is composed of, as shown in FIG. 5, two photoconductive elements R_{01} , R_{02} [composed of] having a composite photoconductive element and constituting photoreceiving portion (i) and [disposed] connected in parallel with each other, and fixed resistance R_x connected in series to photoconductive element R_{01} . The [connection point] junction between [said] composite photoconductive element R_0 and fixed resistance R_x [connected in series thereto] is connected to contact [a for] a of change over switch S_3 in memory circuit (iii) [, and said resistance connection bodies] . Resistances R_0 , R_x are connected to the collector circuit of transistor Tr_3 together with resistance R_2 in parallel therewith and variable resistance R_3 in series thereto [, and the] . The emitter of [said] transistor Tr_3 is connected to the positive side of electric power source E through resistance R_5 to constitute logarithmic compressed circuit (ii).

Transistor Tr_4 [having] has the same base [electric] potential [as that of said] and identical characteristics as that of transistor Tr_3 [is a transistor of the identical characteristic] and the same electric current runs through them [, and by variable] . Variable resistance R_4 connected to the collector of [said] transistor Tr_4 also forms part of adjusting circuit (v) for changing the film sensitivity and stop value. [is constituted] .

55 [To] Capacitors C_1 , C_2 are respectively connected to the emitter and the collector of transistor Tr_2 [having the] which has a fixed base [electric] potential by connecting its base to the collector of first step compensation transistor Tr_1 which connects resistance R_{19} between the base and the collector and resistance R_{10} to the base as a bias resistance [, condensers C_1 , C_2 are respectively connected, and between said condenser] . Between capacitor C_1 and the positive side of electric power source E there is provided trigger switch S_4 which is ordinarily opened and then closed simultaneously with starting of the shutter opening operation [; and in] . In parallel with both [said condensers] capacitors C_1 , C_2 discharge switches S_1 , S_2 are

respectively provided; and the charging voltage of [condenser] capacitor C_2 in reference time integrating circuit (vi) is connected to operation circuit (vii), composed of variable resistance R_4 , [connected in series to said] through discharge switch S_2 and [disposed in said film sensitivity and stop adjusting circuit (v)] is input into the base of transistor Tr_5 in the differential amplifier circuit as the first input [and contact b for]. Contact b of change over switch S_3 in [said] memory circuit (iii) is connected to the base of transistor Tr_6 [as] to provide the second input, and the emitters of both transistors Tr_5 , Tr_6 are connected to the collector of transistor Tr_{13} [and to the emitter of said transistor Tr_{13} resistance]. Resistance R_{12} is connected to the emitter of transistor Tr_{13} , and the base of [said] transistor Tr_{13} is connected to the [connection point] junction between resistance R_{13} and diode D_2 to compensate [the] for changes in temperature [and to the collector of said transistor Tr_5 resistance]. Resistance R_{11} is [inserted] connected to the collector of transistor Tr_5 , and thus comparison circuit (iv) is formed.

[As for] With respect to exposure time control circuit (viii), main switch S_5 of electromagnetic coil M is [provided] connected to electric power source E and a Schmitt circuit composed of Tr_7 , Tr_8 , Tr_9 , and Tr_{10} is formed [and to the base of transistor Tr_7 on the input side thereof the]. The collector of transistor Tr_5 in [said] comparison circuit (iv) is connected [and to the collector of Transistor Tr_{10} on the output side thereof said electromagnetic] to the base of transistor Tr_7 . Electromagnetic coil M is connected to the collector of transistor Tr_{10} , and the moment main switch S_5 is closed transistors Tr_9 , Tr_{10} are [electrified] made conductive and electromagnetic coil M is excited [and the]. The moment transistor Tr_5 in the differential amplifier circuit is reversed transistors Tr_7 , Tr_8 are [electrified] made conductive and transistors Tr_9 , Tr_{10} are cut off and the excitation of electromagnetic coil M is stopped and accordingly the closing operation of the shutter is started.

Meter circuit (ix) is provided with two amplifier transistors Tr_{11} , Tr_{12} to [give the logarithmic elongation by] logarithmically elongate the electric current [to the electric potential] at contact [a for said] a of change over switch S_3 and the bias voltage of condenser C_2 in reference time integrating circuit (vi) [and]. Meter circuit (ix) is composed of double coil ammeter A [which] the coils of which are wound [to the opposite direction] oppositely so as to indicate the difference between the electric potential at contact a and the bias voltage of condenser C_2 , namely, the shutter speed.

FIG. 3 [is a partial view] shows part of FIG. [1] 2 and [shows] the essential portion thereof according to the present invention. At the first stage of the shutter release, switches S_1 , S_2 are [cut off] closed and when trigger switch S_4 is [electrified] closed simultaneously with starting of the shutter opening operation the charging [to condensers] of capacitors C_1 , C_2 is 60 started.

[Now, let us think over] The following describes how the charging voltages V_1 , V_2 of [condensers] capacitors C_1 , C_2 change [in the lapse of] with time from the time when trigger switch S_4 is [electrified] closed, that is, the shutter starts to open. [Provided] Assuming the voltage between the base and the emitter of transistors Tr_1 is V_{BE1} , [this turns to the base elec-

tric potential of transistor Tr_2] and the resistance value of resistance R_{19} is for compensating the voltage and is so small as to be negligible, so that provided the charging voltage of [condenser] capacitor C_1 is V_1 , voltage V_{BE2} between the base and the emitter of transistor Tr_2 is as follows:

$$[V_{BE2}] V_{BE1} = [V_{BE2}] V_{BE2} + V_1 \quad (1)$$

and collector current i of transistor Tr_2 is as follows:

$$[V_{BE2}] V_{BE1} = V_0 \log i + V_1$$

wherein V_0 [and V_1 are respectively] is a [proportion] constant of transistor Tr_2 .

15 And, provided the capacity of [condenser] capacitor C_1 is C_1 , charging voltage V_1 is as follows:

$$V_1 = \frac{1}{C_1} \int_0^t i dt$$

Therefore, from formula (1) the following formula is obtained:

$$[V_{BE2}] V_{BE1} = V_0 \log i + V_1 + \frac{1}{C_1} \int_0^t i dt \quad (2)$$

30 In order to [look for] obtain the relation between i and t , upon differentiating [said] formula (2) with respect to t as V_{BE1} is constant with t ,

$$0 = V_0 \frac{1}{i} \frac{di}{dt} + \frac{1}{C_1} \int - \frac{1}{C_1 V_0} dt = \int \frac{1}{i^2} di - \frac{1}{C_1 V_0} = - \frac{1}{i} + K \quad (3)$$

40 Provided that the characteristics of transistors Tr_1 , Tr_2 are identical and the current running through Tr_1 is I_0 , the collector current of transistor Tr_2 at the moment trigger switch S_4 is [electrified] closed (namely, $t=0$) [turns] is also [to] I_0 , so that K of [said] formula (3) is as follows:

$$K = \frac{1}{I_0}$$

Therefore, from formula (3)

$$\frac{1}{C_1 V_0} = \frac{1}{i} - \frac{1}{I_0} \quad (4)$$

$$i = \frac{1}{\left(\frac{1}{C_1 V_0} + \frac{1}{I_0} \right)}$$

$$C_1 V_1 = \int_0^t i dt = \int_0^t \frac{dt}{\left(\frac{1}{C_1 V_0} + \frac{1}{I_0} \right)}$$

$$= \left[C_1 V_0 \log \left(\frac{1}{C_1 V_0} + \frac{1}{I_0} \right) \right]_0^t$$

$$= C_1 V_0 \left\{ \log \left(\frac{1}{C_1 V_0} + \frac{1}{I_0} \right) - \log \frac{1}{I_0} \right\}$$

$$= C_1 V_0 \log \left(\frac{I_0}{C_1 V_0} + 1 \right)$$

Therefore,

$$C_1 V_1 = C_2 V_2 = C_1 V_0 \log \left(\frac{I_0}{C_1 V_0} + 1 \right)$$

-continued

$$V_1 = V_a \log \left(\frac{1+t}{C_1 V_a} + 1 \right) \quad (5)$$

$$V_2 = \frac{C_1 V_a}{C_2} \log \left(\frac{1+t}{C_1 V_a} + 1 \right) \quad (6)$$

As shown in formula (6) the increase of charging voltage V_2 of the first input [condenser] [capacitor] C_2 is the differential amplifier circuit is in proportion to the logarithmic value of the time from the time when trigger switch S_4 is [electrified] [closed].

In FIG. 4 the relation between charging voltage V_2 of [said condenser] [capacitor] C_2 and the time from the instant [time] when trigger switch S_4 is [electrified] [closed] is shown.

Upon changing the [setting] film sensitivity [setting] and stop value the resistance [value] of variable resistance R_4 undergoes a change and the bias voltage at [the first stage of condenser] [capacitor] C_2 is changed, so that as shown in FIG. 4 the time characteristic of charging voltage V_2 is moved [in] parallel by changing the film sensitivity and stop value.

[By the way] Also, by changing the capacity ratio of [condensers] [capacitors] C_1 , C_2 it is possible to obtain any charging characteristic of [condenser] [capacitor] C_2 .

Photoconductive element R_0 is a composite photoconductive element and formed as shown in FIG. 5, and photoconductive elements R_{01} , R_{02} which are the [formation] elements of [said] photoconductive element R_0 have the characteristic as shown in FIG. 6 relative to the logarithmic value of the illuminance on the light receiving surface, and fixed resistance R_x also has the value as shown in FIG. 6 [therefore]. Therefore, composite photoconductive element R_0 has the characteristic as shown by the thick line in FIG. 6 relative to the logarithmic value of the illuminance on the light receiving surface.

FIG. 7 shows the circuit in the case [of that] where composite photoconductive element R_0 having [the illuminance on the light receiving surface —] the resistance characteristic shown in FIG. 6 is connected in series to fixed resistance R_1 , [and] [FIG. 8 shows the relation between the electric potential (volt) thereof and the illuminance on the light receiving surface [and the]. The electric potential at contact a is [given the logarithmic compression to the illuminance on the light receiving surface] logarithmically compressed and undergoes a change by V_0 relative to the variation of [one grade] 1 EV of the illuminance on the light receiving surface [1 EV].

In the case of the present invention, therefore, by changing the circuit constant of the reference time integrating circuit (for example, the capacity ratio of [condensers] [capacitors] C_1 , C_2 , the base voltage of transistor Tr_2) the slope of the charging characteristic of [condenser] [capacitor] C_2 shown in FIG. 4 is optionally changed and the variation quantity per 1 EV in the logarithmic compression [progress] shown in FIG. 6 can be made [to the highest precision value] precise in accordance with the power voltage used and the photometric range.

[In the case of giving the logarithmic elongation by means of a well known logarithmic elongation element, however, the variation quantity in the logarithmic compression progress for changing 1 EV by the output in the elongation progress is restricted by the characteris-

tic of the logarithmic elongation element and the variation quantity in the logarithmic progress is little and the precision in the elongation progress gets worse.]

[For example, according] According to the experimental data of this inventor, in the case [of that] where a transistor is [put to use] used in the logarithmic elongation process the variation quantity per 1 EV of the input [in the logarithmic elongation progress] is restricted to 18 mV at the base voltage because of the characteristics of the base voltage and the collector current of the transistor [however]. However, when a comparison circuit according to the present invention is [put to use] used the variation quantity per 1 EV in the logarithmic compression process can be optionally changed [therefore]. Therefore, [under the condition] assuming that the film sensitivity is on eleven grades (from ASA6 to ASA6400), the stop value on eight grades (from F14 to F16), the shutter speed on eleven grades (from 1/1000 second to 1 second), and the power voltage is 3V, the variation quantity per 1 EV in the logarithmic compression process can be made to 80 mV.

Therefore, the variation quantity per 1 EV in the logarithmic compression [progress] becomes [is] more and accordingly [the] exposure time control [in] with high precision becomes possible.

Besides, in the case of the present invention; the information of the film sensitivity and stop value is [impressed in] provided to the first input of the differential amplifier circuit as the bias voltage for [condenser] [capacitor] C_2 , and to the second input of the differential amplifier circuit the information of the illuminance on the light receiving surface of the photoconductive element is added [in being given the] after logarithmic compression [therefore]. Therefore, after the [photometry] initial photometric measurement is [given with the opening photometry] made, when [seeing] observing the focal depth by stopping down the diaphragm diameter of an exchange lens the illuminance on the light receiving surface of the photoconductive element is [memorized] stored in [memory condenser] [storage capacitor] C_3 by connecting switch S_3 to contact b from contact a, and then even though the stop value is changed to the desired focal depth the information of the stop value [interlocks with condenser] is stored by capacitor C_2 as [the] a bias voltage and has no relation to [memory condenser] [storage capacitor] C_3 , so that even after being stopped down it is possible to change to any stop value.

FIG. 9 is a perspective view showing the essential portion of the embodiment of the mechanical interlocking [relation] relationship between the shutter mechanism, [and] the electromagnetic resistance, [body], the switch, [and so on] etc., in the case [of that] where the exposure time control circuit shown in FIG. 2 is applied to a "through the lens" photometric type focal plane single reflex camera.

In the photometric state, ammeter A indicates the exposure time. Photoconductive element R_0 is provided on pentagonal prism 1 [to do photometry] for the photometric measurement.

Now, upon pushing shutter button 2 interlocking lever 3 is pushed down and lever 5 is turned counter-clockwise by interlocking rod 4 to disengage from switch lever 6 having [the] a turning tendency [to] in the direction shown by arrow CW_3 [and pin]. Pin 7a of insulation member 7 attached to

【 said 】 switch lever 6 【 to switch over switches 】 changes over change over switch S_3 to contact b from contact a and simultaneously cuts off switches S_1 , S_2 , and thereby enabling the charging 【 to condensers 】 of capacitors C_1 , C_2 【 becomes possible 】.

After change over switch S_3 is 【 cut off 】 switched from contact a, 【 said 】 pin 7a of insulation member 7 【 electrifies 】 actuates main switch S_5 to excite electromagnetic coil M.

After main switch S_5 is 【 electrified 】 actuated switch lever 6 turns mirror lever 9 【 to 】 in the direction shown by arrow CW_4 through intermediate lever 8 to let spindle 10 turn reflector 11 【 to 】 in the same direction. And accordingly, by the turning of 【 said 】 reflector 11 the photometric state is changed over to the photographic state and the quantity of incident light to photoconductive element R_0 decreases gradually 【, however 】. However, change over switch S_3 has already changed over to contact b from contact a, so that 【 memory condenser 】 storage capacitor C_3 has 【 memorized 】 stored the signal representing the resistance of photoconductive element R_0 【 at the photometric state 】.

【 In the final progress 】 Finally, mirror lever 9 engages with release lever 12 to turn it, and the pawl of opening screen restraining lever 13 disengages from restraining plate 14, and 【 said 】 restraining plate 14 turns together with the opening screen shaft, having 【 the 】 a turning tendency 【 to 】 in the direction shown by arrow CW_2 , through spindle 15 and gears 16, 17, and opening screen 22 starts to open the shutter. And, at the same time protuberance 18 provided fixedly on 【 said 】 spindle 15 turns counter-clockwise to close trigger switch S_4 for 【 condensers 】 capacitors C_1 , C_2 , so that the charging 【 to condensers 】 of capacitors C_1 , C_2 is started.

However, the closing screen is 【 in being 】 checked 【 to run 】 from moving by closing screen restraining lever 19 attracted by electromagnetic coil M.

When the voltage of 【 condenser 】 capacitor C_2 【 gets 】 charges to the 【 memory 】 same voltage 【 of condenser 】 as capacitor C_3 electromagnetic coil M is demagnetized and rear screen restraining lever 19 is turned clockwise by spring 20 so as not to engage with pin 21a and 【 permit 】 permits gear 21 to turn, so that shutter closing screen 24 starts to 【 run 】 move through gear 23 to close the shutter.

Upon turning winding lever 25 counter-clockwise, the film (not shown in the drawing) is wound and at the same time gear 16 is rotated clockwise through gear 26 integral to winding lever 25, gear 27, gear 28, and gear 29, and gear 21 also is rotated through pin 16a and pin 16b 【, and when 】. When restraining plate 14 integral to gear 16 engages with the pawl of opening restraining lever 13 the shutter 【 charge 】 cocking is finished.

When the shutter 【 charge 】 cocking is finished pin 16b of gear 16 turns lever 30 counter-clockwise, and closing screen restraining lever 19 integral to lever 30 is turned counter-clockwise against spring 20 to form the well known holding 【 magnet 】 mechanism.

【 As 】 With respect to interlocking wire 34, one end thereof is connected to pulley 33, rotated in a body with film sensitivity setting dial 31 by spindle 32, and the other end thereof is secured to diaphragm setting ring 37 on the lens barrel through pulley 36 pivoted on arm portion 35a 【 projected to 】 projecting in the radius direction from gear 35 fitted loosely on 【 said 】

spindle 32. And, slide brush 39 provided on the insulation spindle of gear 38 meshed with 【 said 】 gear 35 is arranged to slide on variable resistance R_4 .

Therefore, upon setting up the film sensitivity by film sensitivity setting dial 31 and setting up the stop value by diaphragm setting ring 37, slide brush 39 slides on variable resistance R_4 【 so as 】 to 【 get to the 】 provide resistance value corresponding to the setting film sensitivity and the setting stop value. 【 By the way, brush 】 Brush 40 is a fixed brush.

When using the camera, electric power switch S_1 is 【 electrified 】 closed. The mechanism for changing over switch S_3 to contact b from contact a when stopping down the diaphragm diameter for the exchange lens is simple so that it is omitted in the drawings.

FIG. 10 shows 【 an 】 another embodiment in accordance with the present invention, wherein instead of the light receiving element in the photometric circuit shown in FIG. 5 two composite photoconductive elements R_0 , R_0' are connected in series 【, and 】. And provided that the elements 【 for constituting said 】 comprising composite photoconductive elements R_0 are R_{01} , R_{02} and the elements 【 for 】 constituting the other composite photoconductive element R_0' are R_{03} , R_{04} , the illuminance — resistance characteristics of each respective element is as follows:

$$R_{01} = R_{03} = K_1 L^{-\gamma}, R_{02} = R_{04} = K_2 L^{-\gamma}$$

30 【 and, by said 】 Using both composite photoconductive elements the photographic field is divided 【 to do photometry 】 for the photometric measurement, and thereby for objects different in 【 the 】 their brightness ratio the proper average photometry can be effected.

What is claimed is:

1. An automatic shutter control device for a single lens reflex camera of the type having a photoconductive member receiving light from an object to be photographed via an objective lens, comprising:

means for generating a first output voltage proportional to the logarithm of intensity of light incident on said photoconductive member;

means for storing said first output voltage;

means for separating said means for storing from said means for generating a first output voltage with the shutter release operation;

means for generating a second output voltage as a function of a manually set exposure condition; a transistor;

means for applying constant voltage to the base of said transistor;

a first integrating means connected to the emitter of said transistor for generating a signal that changes in proportion to the logarithm of an elapsed time period initiated by the shutter release operation;

means for initiating operation of said first integrating means in response to the shutter release operation;

means for generating a control signal when said signal 【 plus 】 relative to said first and second output voltages 【 are substantially equal to said first output voltage 】 provides a proper exposure; and

means for actuating shutter closing operation in response to said control signal.

65 2. An automatic shutter control device as in claim 1, further comprising second integrating means connected to the collector of said transistor for generating a third output voltage which changes in response to the

change of said signal of said first integrating means, and said means for generating a control signal includes a comparing circuit for comparing said signal plus said second output voltage with said first output voltage.

3. An automatic shutter control device as in claim 2, wherein said photoconductive member comprises two parallelly connected photoconductive elements and said means for generating a first output voltage includes said photoconductive elements, a compensation resistor connected to at least one of said photoconductive elements and an output resistor connected to said compensation resistor to generate said first output voltage.

4. An automatic shutter control device as in claim 3, wherein said comparing circuit includes a differential amplifier circuit having a first input terminal to which said first output voltage is applied and a second input terminal to which both said second and third output voltages are applied and said means for generating a second output voltage biases said second integrating means.

5. An automatic shutter control device as in claim 4, further comprising an electric power source and said means for applying constant voltage includes a second transistor connected between said power source by the emitter and collector thereof and having a base connected to the collector of said second transistor through a resistor, the base of said first transistor being connected to the collector of said second transistor.

6. An automatic shutter control device as in claim 5, wherein said means for generating a first output voltage further includes means for generating a constant current, and said means for generating a second output voltage includes a variable resistor and said constant current flows through said variable resistor.

7. An automatic shutter control device as in claim 6, wherein said first and second integrating means are adjustable for changing the ratio of their respective stored signals.

8. An automatic shutter control device as in claim 7, further comprising means for indicating shutter speed prior to shutter release and responsive to said means for generating a first output voltage.

9. An automatic shutter control device as in claim 8, wherein said means for indicating shutter speed comprises an ammeter having double coils and two transistors in which each collector thereof is connected to a

respective one of said double coils, and the base of one of said transistors is connected to said means for generating a first output voltage and the base of the other transistor is connected to said means for generating a second output voltage.

10. An automatic shutter control device for a single lens reflex camera of the type having a photoconductive member receiving light from an objective to be photographed via an objective lens, comprising:

- an electric power source;
- a detecting circuit including said photoconductive member connected to said electric power source for generating a first output voltage proportional to the logarithm of intensity of light incident on said photoconductive member;
- a change over switch;
- a storage means connected to said detecting circuit through said change over switch prior to exposure of the shutter for storing said first output voltage;
- means including a variable resistor for generating a second output voltage as a function of an exposure condition manually set in the camera;
- a transistor;
- means for applying a constant voltage to the base of said transistor;
- a first capacitance connected to the emitter of said transistor so that terminal voltage of said capacitor changes in proportion to the logarithm of an elapsed time period;
- means for initiating the change of said terminal voltage of said first capacitor in response to opening operation of the shutter;
- a second capacitor connected to the collector of said transistor and switch means for connecting said collector to said means for generating a second output voltage;
- a differential amplifier circuit having two transistors, the base of one of said transistors is connected to the collector of said transistors and the base of the other transistor is connected to said storage means through said change over switch interlocked with the opening operation of the shutter for generating an output signal when the base potentials of both said transistors are substantially equal; and
- an electromagnet for terminating exposure and responsive to said output signal.
